[57] CLAIM

The ornamental design for a programmable electronic circuit breaker, as shown and described.

DESCRIPTION

FIG. 1 is a top perspective view of a programmable electric circuit breaker showing my new design; FIG. 2 is a side elevational view thereof, the opposite side elevational view being a mirror image; FIG. 3 is a left end elevational view thereof, the right end elevational view being a mirror image except for the exposed portion of the key pad; and FIG. 4 is a top plan view thereof.

FIG. 2

FIG. 1

FIG. 3

FIG. 4
